METHOD OF AND MACHINE FOR LASTING
BOOTS AND SHOESCarl F. Hammann, Boston, Mass., assignor to
North American Holding Corporation, Syra-
cuse, N. Y., a corporation of New York

Application September 9, 1940, Serial No. 355,964

48 Claims. (Cl. 12-2)

My invention relates to boot and shoe lasting machines of that class which is constructed with a pair of driven rolls between which the marginal portion or skirt of a shoe upper is gripped and by which it is fed laterally while said shoe upper and an innersole are in position upon a last. In operating a machine of this class the last with said shoe parts mounted thereon is held in proper position relatively to said rolls by an operative who directs and controls the lateral movement of the last so that said rolls not only traverse the skirt of the shoe upper but also pull or stretch the latter around the corner of the last and lay it down on to the innersole to which it is secured as the pulling-over operation progresses.

My invention provides an improved boot and shoe lasting machine of the class indicated which, in the preferred form of the invention, may be constructed and operate as set forth in the following description, the several novel features of the invention being separately pointed out and defined in the claims at the close of the description.

In the accompanying drawings:

Figure 1 is a front elevation, partly broken away and in section, of a boot and shoe lasting machine embodying this invention.

Figure 2 is a front elevation of part of the lower portion of the machine shown in Fig. 1.

Figure 3 is a side elevation, partly broken away and in section, of the machine shown in Fig. 1.

Figure 4 is a detail relating to part of the mechanism shown in Fig. 3.

Figure 5 is a front elevation of the "head" of the machine shown in Figs. 1 and 3, with the housing, hereinafter referred to, removed.

Figure 6 is a detail illustrating the construction of the two clutch levers hereinafter described.

Figure 7 is a section on line 7—7 of Figs. 5 and 8.

Figure 8 is a top plan view of the head shown in Figs. 5 and 7.

Figure 9 is a section on line 9—9 of Fig. 7.

Figure 10 is a section on line 10—10 of Fig. 8.

Figure 11 is a partial section on line 11—11 of Fig. 10.

Figure 12 is a section on line 12—12 of Fig. 9.

Figure 13 is a section on line 13—13 of Fig. 9.

Figure 14 is a section on line 14—14 of Fig. 9.

Figure 15 is a section approximately on line 15—15 of Fig. 5.

Figure 16 is an enlarged elevation of one of the staples hereinafter referred to.

Figure 17 shows a length of wire such as is employed in producing the staple of Fig. 16.

Figure 18 is a fragmentary sectional view, enlarged, illustrating the construction of the lower

wire feeding and wire roughening roll hereinafter described.

Figure 19 is a detail in plan, full size, showing the staple feeding slide and the magazine hereinafter described.

Figure 20 is a side elevation of the magazine for holding a file of staples from which they are delivered, one at a time, to the staple driving mechanism described later.

10 Figure 21 is a plan view of the magazine, but with its top wall removed and partly in section.

Figure 22 is an elevation of the rear end of the magazine shown in Fig. 20.

15 Figure 23 is a section on line 23—23 of Fig. 20.

Figure 24 is a section on line 24—24 of Fig. 20.

15 Figure 25 is an elevation of the front end of the magazine.

20 Figure 26 is a side elevation, enlarged, illustrating the construction of the pair of feed rolls hereinafter described.

The illustrated embodiment of the invention comprises a column 10 (Figs. 1 and 2) provided at its lower end with a hollow pedestal 11 and at its upper end with a head 12.

25 The column 10 comprises four corner posts 13 fastened at their lower ends to the top of pedestal 11 and at their upper ends to a frame 14 forming part of head 12. To these corner posts are fastened sheet metal panels 15, said panels

30 and posts providing a columnar housing section for inclosing certain parts of the machine.

The frame 14 of the head has fastened to it the parts of a sectional sheet metal housing 16 by which most of said frame and other parts of

35 the mechanism are inclosed.

A shelf 17 and drawer 17a are provided upon the exterior of the front of column 10 for the convenience of the workman, said drawer being slidably mounted within a compartment provided 40 upon the under side of the shelf.

A pair of upper-gripping rolls 18 and 19 (Figs. 1, 2, 11 and 15) are supported in position at the front of the frame 14 of head 12 where they are accessible to the operator who stands in front

45 of the machine holding a last 20 (Fig. 15) to which an innersole 21 and upper 22 have been applied. The axes of these two rolls are preferably disposed in one vertical plane.

The rolls 18 and 19 are momentarily separated 50 by depression of a foot lever 24 (Figs. 1 and 2) to permit entry of the flange or skirt 23 of the upper between said rolls after which rotation of the rolls feeds said flange or skirt laterally carrying the innersole and last with it.

55 As the rolls 18 and 19 traverse the skirt of the upper the side of the shoe is manually held against a guide roll 25 rotatably mounted upon the frame 14 of the head 12, while the upward pull of said rolls upon the skirt or flange 23 holds 60 the innersole 23 snugly against the convex lower

end of the roll 19 which therefore also serves as a shoe guiding abutment.

The upper-pulling action of the rolls 18 and 19 is occasioned by manually maintaining the shoe in a slightly laterally tilted position relatively to the plane of the axes of the rolls so that the portion of the flange of the upper that is approaching the bite of said rolls is somewhat higher than the portion thereof that is at the opposite side of the rolls. As a result the shoe is not only fed laterally but it is also yieldingly urged upwardly toward and against roll 19 while the operator holds the shoe against guide roll 25. These actions of the feed rolls, combined with the lateral pressure exerted by the operator in holding the shoe against the guide roll 25, stretches the upper around the corner of the last and lays a portion of the skirt or flange thereof down on to the innersole, as shown in Fig. 15, where it is secured either by cement or by fastener elements, or by both cement and fastener elements if desired.

The fastener elements employed may, as herein contemplated, consist of wire staples which are automatically fabricated and driven into the upper skirt and innersole as the pulling over operation progresses, and the mechanism embodying this feature of the invention includes a staple driver 26 (Figs. 5 and 15) disposed closely alongside of the feed rolls 18 and 19 and partly behind the roll 18.

This driver 26 occupies a position between the feed rolls and a wiper element 27 (Figs. 5, 7 and 9) provided at its upper end with a laterally projecting trunnion 28 by which it is pivotally mounted on head frame 14.

As will presently be explained, control mechanism is provided through which the operator may at will adjust the machine so as to cause the feed rolls 18 and 19 to be continuously rotated in unison in the directions of the arrows in Fig. 15 while the staple making and driving mechanism is out of action and at rest, or so as to continually actuate said rolls intermittently or step-by-step, in the directions indicated while the staple making and driving mechanism is in action producing and driving a staple during each period of rest of the rolls.

The wiper element 27, however, is continuously vibrated at all times while the machine is in use under either condition of adjustment and serves to wipe the skirt of the upper down on to the innersole as or just after it leaves the feed rolls.

At the rear thereof the head frame 14 is provided with an upstanding bracket extension 14a (Figs. 7, 8 and 10) made with bearings within which is journaled a vertically disposed continuously driven prime power shaft 29 having a pinion 30 fixed on its lower end portion and a worm 31 fixed on its upper end.

The worm 31 continuously drives a worm gear 32 loosely mounted on a horizontal shaft 33, but adapted to be coupled thereto, as described later, so that said shaft is, at times, rotated by and with said worm. Shaft 33 is journaled at its one end in a bearing provided at the top of bracket extension 14a and near its opposite end in a bearing provided at the top of an upstanding wall 14b forming an integral part of head frame 14.

The staple making and driving mechanisms are actuated by this horizontal shaft 33 which, at times, also serves to actuate the feed rolls 18 and 19 intermittently through the medium of a second horizontal shaft 34 (Figs. 7 and 11) connect-

ed with feed roll 19, and a third horizontal shaft 35 carrying the other feed roll 18.

At its front end the shaft 34 is connected by beveled gears 36 with the upper end of a shaft 37 which extends obliquely downwardly from said gears to the other feed roll 19 which forms a rigid part thereof.

The forward end of the second horizontal shaft 34 is rotatably supported by a bearing 38 provided upon a carriage 39 that is slideable horizontally, in ways provided upon the wall or upstanding extension 14b of the head frame 14, in a direction parallel with shaft 34, while the oblique shaft 37 is also journaled in bearings provided upon said carriage. The gears 36 are completely inclosed within a grease-holding chamber 40 provided upon the carriage 39.

The lower, or third, horizontal shaft 35 is journaled within a bearing provided in the base portion of the head frame 14 and is provided at its rear end with a bevel gear 41 in mesh with and driven by a bevel gear 42 fast on a second vertical shaft 43 whose upper portion is journaled in a bearing provided within the rear upstanding bracket extension 14a.

At its upper end shaft 43 is provided with a bevel gear 44 meshing with a bevel gear 45 having an elongate tubular hub journaled in a bearing 46 provided upon the front section of bracket extension 14a of the frame.

The tubular hub of gear 45 is made with a longitudinal slot 47 that is occupied by a key 48 projecting radially from the second horizontal shaft 34 so that the latter may be moved axially within said hub, but must rotate with it. In other words, the rear end of shaft 34 is telescopically fitted within and splined to the tubular hub of gear 45.

The hub of gear 45 includes, as a rigid part thereof, a collar 49 made with a circular radial flange 50 (Figs. 6 and 11) which is confined within the hub of a clutch lever 51 that is pivotally supported by the hub of gear 45 and provided upon its interior with clutch elements 52 cooperating with the periphery of flange 50 so that upward swinging movement of lever 51 acts through the clutch elements to turn gear 45 and shaft 34 with it, while movement of the clutch lever in the opposite direction is effected independently of gear 45 and shaft 34. Thus the lever 51 may be regarded as of the over-running type since it is possible for shaft 34 to be rotated continuously in the direction of the arrow (Fig. 6) independently of the clutch lever, as presently to be described.

As shown in Figs. 5 and 7, the clutch lever has pivotally connected to it a pitman 53 whose strap embraces a double eccentric 54 fast on the upper horizontal shaft 33. Thus, when shaft 33 is rotated it will act through eccentric 54 and pitman 53 to vibrate lever 51 and the latter will act through its clutch mechanism and the hub of gear 45 to rotate the second horizontal shaft 34 step-by-step in the direction indicated by the arrow in Fig. 7. As will be clear, this intermittent movement of shaft 34 will be transmitted through gears 36 (Fig. 11) to shaft 37 carrying feed roll 19 and through gears 45 and 44, shaft 43 and gears 42 and 41, to shaft 35 carrying feed roll 18.

The worm gear 32 at the rear end of shaft 33 is continuously driven by the worm 31 on the prime power shaft 29 (Figs. 7, 8 and 10) and one end of its hub is made with crown teeth 55 to cooperate with a bolt 56 which is yield-

ingly urged toward said hub by a spring 57, said spring and bolt being parts of a coupling clutch that is indicated generally at 58. This coupling clutch comprises inner and outer body members, as shown in Fig. 7, which are rigidly fastened together and to shaft 33, the double eccentric 54 being an integral part of the outer body member of said coupling clutch 58.

Co-operatively disposed with respect to coupling clutch 58 is a bolt-operating member 59 herein shown as in the form of a lever pivotally connected intermediate its ends as at 60 to one side of the bracket 14a. One arm of member 59 occupies an annular groove 61 provided upon the exterior of the body of coupling clutch 58 across which groove the bolt 56 extends. The extremity of this arm of member 59 is made wedge-shaped so as to provide a cam surface 61' (Fig. 8) against which a shoulder 62 on bolt 56 rides when said arm is swung downwardly into the path of the bolt. This retracts bolt 56 against the pressure of its spring 57 (Fig. 7) thereby disconnecting the continuously rotating worm gear 32 from shaft 33 and stopping the latter.

The other arm of member 59 is connected by an endwise extensible and contractible link 63 with an arm 64 (Figs. 1, 2, 9 and 10) fast on one end of a rock-shaft 65. Fastened to the opposite end of rock-shaft 65 is another arm 66 to which is pivotally connected one end of a link 67 which extends downwardly into column 10 where its lower end is pivotally connected to an arm 67a fast on a rock-shaft 68. A spring 69 connected with a second arm 70 projecting from shaft 68 acts through the connections described to yieldingly urge link 67 upwardly.

Rock-shaft 68 is provided with a third arm 71 provided at its free end with a truck or roll which, at all times, is held against a cam 72 projecting upwardly from a slide-bar 73 movably supported by a bearing 74 fixed to one of the side walls of column 10.

Slide-bar 73 extends through bearing 74 to the exterior of column 10 where it is provided with a leg pad 75 of rubber or the like mounted within a pad-holder 76 that is made upon its rear side with a threaded stem 77. This stem extends through a slot 78 (Fig. 2) provided in an arm 73b projecting radially from slide-bar 73. As will be clear, holder 76 may be adjusted lengthwise of slot 78 to suit the convenience of the operator and fixed in its adjusted position by two nuts mounted on stem 77.

A coiled spring 80 mounted upon the inner end portion of slide-bar 73 bears at its one end against the inner side of one of the walls of column 10 and at its opposite end against a collar 73a on slide-bar 73, and normally this spring yieldingly holds the slide-bar at the limit of its outward movement, as shown in Fig. 4.

In the drawings, however, the slide-bar is shown at the limit of its inward movement where it is held, against the pressure of spring 80, by one leg of the operator as indicated in Fig. 3 of the drawings. When the slide-bar 73 occupies this position, the arm 71 is supported by the highest elevation of cam 72; link 67 is at the limit of its downward movement, and the inner cam arm of bolt-operating member 59 of head 12 is held out of engagement with clutch bolt 56 (Figs. 7 and 8). Therefore, shaft 33 is coupled to the continuously rotating worm gear 32 and shafts 34 and 35 are being intermittently actuated to feed the work step-by-step past the

feed rolls 18 and 19. While operating under these conditions the staple making and driving devices are in action also.

As shown in Figs. 9 and 10 the rock-shaft 65 carrying the arms 64 and 66 is journaled in bearings provided upon a box-like bracket 81 fixed in position against the bottom side of the head frame 14 and within said bracket the shaft 65 has fixed on it a forked arm or yoke 82 which embraces a clutch member 83 splined on the shaft 43 referred to above. Loosely mounted within an annular groove (not shown) provided upon the exterior of clutch member 83 is a collar 84 to the opposite sides of which the tines of yoke 82 are pivotally connected.

It will now be clear that the yoke 82, rock-shaft 65 and the two arms 64 and 66 provide a rigid shipper unit that is manually operated and controlled through the medium of the leg-operated slide-bar 73 and that this unit serves the double function of operating clutch member 83 and bolt-retracting member 59.

The link 63 (Fig. 10) comprises a rod or stem 85 whose upper end is pivotally connected to the outwardly extending arm of bolt-operating member 59 and whose lower end is provided with a head 86 disposed within a sleeve 87 telescopically fitted on the lower end of stem 85. The lower end of this sleeve is closed and pivotally connected to arm 64 while its upper end is occupied by a tubular plug 88 having threaded engagement with the interior of the sleeve. Normally the head 86 is yieldingly held against the inner end of plug 88 by a spring 89 confined within the sleeve.

The purpose of this construction will presently appear, but it may be noted here that when the shipper unit 64—66—82 occupies the position shown in Fig. 10 clutch member 83 occupies an inoperative position at the time of its upward movement on shaft 43, the cam arm of member 59 is above the path of bolt 56, and shaft 33 is being driven in the direction of the arrow.

It will also be noted that if the arms 64—66 are swung upwardly far enough to lower the cam arm of member 59 into its operative position against the bottom of the groove 61 (Fig. 8) where it retracts bolt 56, rotation of shaft 33 will be stopped and clutch member 83 (Fig. 10) will occupy an idle intermediate position.

Also, continuation of upward movement of arm 64 beyond such intermediate position will compress spring 89 and at the same time cause yoke 82 to shift clutch member 83 downwardly to the limit of its movement in that direction where its teeth are meshed with the teeth of a complementary clutch member 90 herein shown as the hub of a gear 91 that is continuously driven by the gear 30 that is fast on the prime power shaft 29. The gear 91 loosely surrounds the shaft 43 and its hub is in part journaled in a bearing provided in the bottom wall of the box-like bracket 81.

As shown in Fig. 4 the cam 72 on slide-bar 73 is formed with two elevations 92 and 93 of different heights between which there is provided a depression or socket 94.

When slide-bar 73 is held at the limit of its outward movement by spring 80 as in Fig. 4 the arm 71 is supported by the lower elevation 93 and acts through the connections described to hold clutch member 83 in an idle intermediate position with the cam arm of member 59 seated within groove 61 so that shafts 33, 34, 35, 37 and 43 are at rest; when slide-bar 73 is adjusted in-

wardly to a position where arm 71 (Figs. 3 and 4) is supported within socket or depression 94, said arm acts through the connections described to move clutch member 83 downwardly into mesh with clutch member 90 with spring 89 (Fig. 10) compressed so that the cam arm of member 59 remains in its operative position at the bottom of slot 61 (Fig. 8), with shaft 33 at rest and shafts 34, 35, 37 and 43 rotating continuously, and when slide-bar 73 is adjusted inwardly to the limit of its movement in that direction the arm 71 is supported by the highest elevation 92 and acts through the connections described to maintain clutch 83 and bolt-operating member 59 in the positions shown in Fig. 10.

Thus, by means of the single control member 73 and associated parts the operator may at will cause the shafts 34, 35, 37 and 43 to be driven intermittently from shaft 33 by holding said control member at the limit of its inward movement, as shown in Fig. 3; by permitting spring 80 to hold said control member at the limit of its outward movement as shown in Fig. 4, shafts 33, 34, 35, 37 and 43 will be maintained at rest, and by holding the control member 73 in an intermediate position said shafts 34, 35, 37 and 43 will be driven continuously while shaft 33 remains at rest.

While shaft 34 is being driven intermittently by shaft 33 acting through pitman 53 and the one-way clutch lever 51 it is operated by each up-stroke of said lever and while it is being driven continuously in the same direction by gear 91 (Fig. 10) the shaft 33, pitman 53 and clutch lever 51 are at rest and said shaft 34, together with the elongate hub of gear 45 within which it is splined (Fig. 11) are free to over-run or rotate within the clutch hub of said lever.

A supply of wire W from which the staples, hereinabove referred to, are produced is held upon a spool 95 (Figs. 5 and 8) rotatably mounted upon a spindle 96 projecting forwardly from an upstanding bracket 97 fixed in position upon the top of the head frame 14.

Removably mounted upon, and interlocked with, the front end of spindle 96 is a collar 98 against which spool 95 is yieldingly urged by a coiled spring 99 that is mounted on spindle 96 between said spool and bracket 97. Thus spring 99 and collar 98 co-act to impose a frictional braking action on the spool which prevents overrunning of the latter.

The wire W extends from spool 95 through a guide 100 fixed to frame 14 by which it is directed between a pair of intermittently operated feed rolls 101 and 102. From the feed rolls the wire passes through a second guide 103 by which its advance end portion is directed into position immediately above an anvil 104a (Figs. 14, 15 and 19) where it occupies a position between said anvil and a vertically movable bifurcated die 105, at a moment when said die occupies a position above that shown in Fig. 14 out of the path of the wire.

The anvil 104a is a vertically disposed fin provided upon the top side of a hardened steel block 104 fixed in position within a recess provided in head frame 14, with the fin disposed at right angles to the wire as the latter is fed into position above the same as shown in Fig. 19.

The guide 103 (Figs. 5 and 9) is formed upon its bottom side, for a portion of its length, with a groove 106 and this grooved portion fits against the top of a fixed knife blade 107 that is rigidly and adjustably fastened in position upon head

frame 14 by a screw 108 engaging the end thereof and a clamp plate 109 engaging the side of the same, said clamp plate being held in blade-clamping position by a screw as shown in Fig. 5.

5 The groove 106 and blade 107 provide a wire-confining and wire-directing passageway disposed at right angles to the anvil fin 104a through which the wire is intermittently fed by feed rolls 101 and 102.

10 At its inner end knife blade 107 is made with an oblique cutting edge 110 with which a complementary oblique cutting edge 111 (Fig. 14) provided at the lower end of die 105 co-acts to shear the wire diagonally so that the opposite 15 ends of each staple blank produced at the anvil 104a are pointed as shown in Fig. 17. The oblique cutting edge 111 at the lower end of die 105 is formed by beveling one side of the die as shown at 113 (Fig. 14).

20 The die 105 is rigidly clamped within a recess 114 (Figs. 14 and 15) provided at one end of a cross-head 115 by means of a screw 116 engaging the upper end thereof and a screw 117 engaging the outer face of said die, the latter being formed with a longitudinal slot 118 that is occupied by the shank of screw 117 so as to provide for accurate setting of the die with respect to anvil 104a when cross-head 115 occupies its lowermost position.

25 The upper end of the staple driver 26, hereinabove referred to, is rigidly clamped (as shown) to the opposite end of cross-head 115.

The cross-head 115 (Figs. 7, 14 and 15) is slidably mounted upon a pair of vertically disposed 30 guide bars 119 fixed at their opposite ends to the head frame 14 and between said bars it is pivotally connected at 120 to the lower end of a connecting rod 121 by which the cross-head is 35 connected with the wrist pin 122 of a crank-arm 123. The hub of this crank-arm is loosely 40 mounted upon the forward end of the upper horizontal shaft 33 which is continuously driven when the feed rolls 18 and 19 are being intermittently driven but which is at rest while said 45 feed rolls are being continuously driven.

A circumferential slot 124 (Figs. 7, 8 and 14) is provided in the hub of crank-arm 123 and this slot is occupied by a radial lug or arm 125 that is a rigid part of shaft 33. During one-half of each revolution of shaft 33, while the latter is in use, the lug 125 traverses slot 124 in the direction of the arrow in Fig. 14 until said lug engages the end wall 126 of slot 124. Thereafter, during the last half revolution of said shaft the lug or arm 125 swings crank-arm 123 upwardly until wrist-pin 122 passes dead-center position above shaft 33 whereupon the crank-arm is thrown downwardly and returned to its normal position by a pair of coiled springs 127 each of which is mounted upon one of the guide-bars 119.

55 During the upward swing of crank-arm 123 the springs 127 are compressed between the head frame and cross-head 115 so that as the wrist pin 122 passes dead-center position above shaft 33, the cross-head is thrown downwardly by the springs independently of lug or arm 12 with sufficient force to cause die 105 to cut a staple blank (Fig. 17) from the advance end of the wire W and form it into a staple S (Fig. 14) on anvil 104a. Simultaneously, the driver 26 (Fig. 70) is caused to drive a previously made staple into the shoe upper and innersole.

These staple making and driving operations occur simultaneously during each period of rest 75 of the feed rolls 18 and 19 and between step

movements of the wire W effected automatically as presently to be described. That is to say, during each revolution of shaft 33 the wire W is automatically advanced a distance equal to the length of a staple and at about the same time the work is advanced by the feed rolls 18 and 19 a predetermined distance equal to the desired distance between the staples that are driven into the work, after which the cross-head 115 is operated to simultaneously form one staple on the anvil 104a and drive another previously made staple into the work.

Fixedly mounted upon the rear end of the cross-head 115 is a vertically disposed cam 128 (Figs. 7 and 15) co-operating with a bell-crank lever 129 fulcrumed at 130 upon the upstanding wall 14b of the head frame 14. The shorter arm of this bell-crank carries a truck or roll 131 which bears against the cam 128 while the other longer arm of said bell-crank extends downwardly into an aperture 132 formed in a feed slide 133 movable endwise within a groove or channel 134 formed upon the top side of the base portion of the head frame 14. At its one end the slide 133 is forked to provide a pair of longitudinally disposed tines 135 disposed upon opposite sides of anvil 104a as shown in Fig. 19.

The rear end portion of slide 133 is formed with a longitudinal chamber 136 within which is arranged a coiled spring 137. The forward end of this spring bears against the inner end wall of chamber 136 while its opposite end bears against a lug 138 which projects downwardly into groove 134 from a plate 139 fastened by screws to the base portion of frame 14 as shown in Fig. 9. The spring 137 yieldingly urges the feed slide 133 toward anvil 104a and also maintains the truck or roll 131 in engagement with the cam 128.

When the cross-head 115 is moved upwardly, as above described, there is a staple S occupying a position upon the anvil 104a which was produced during the preceding revolution of shaft 33 and as cross-head 115 moves upwardly the cam 128 permits the spring 137 to move the feed slide 133 toward the right in Fig. 15 so that its tines 135 act to shove the previously formed staple S off from anvil 104a and on to a rail 140 forming part of a magazine which is illustrated in detail in Figures 19 to 25, inclusive, said rail 140 abutting one end of anvil 104a and being alined therewith so that it, in effect, constitutes a staple-holding continuation thereof.

Before the cross-head 115 is driven downwardly by the springs 127 the wire W is fed forwardly a distance equal to the desired length of the staple blank and after this feeding movement of the wire the cross-head 115 is driven downwardly by its springs 127 and the die 105 first severs the staple blank from the advance end of the wire W and thereafter folds the opposite ends thereof downwardly against the opposite sides of the anvil 104a.

When the advance end of the wire is fed forwardly as described, it comes into position between the top of anvil 104a and a shoe 141 that is pivotally mounted at 142 upon the plate 139. Therefore, when cross-head 115 is driven downwardly by springs 127, the opposite ends of the blank are first folded downwardly against the opposite sides of the anvil and thereafter the die 105 drives the shoe 141 downwardly forcibly against the top intermediate portion of the staple. When a staple is formed over the anvil there is a tendency for the said intermediate portion to arch across the top of the anvil and 75

it will therefore be clear that when the shoe 141 is driven down on to said top, the latter is straightened so that it is approximately at right angles with respect to the legs of the staple.

5 A spring 143, bearing against the top of shoe 141 at the rear of the pivot 142, serves to elevate the staple-engaging end of said shoe so as to position it above the path of the incoming wire when cross-head 115, with the die 105, is moved upwardly as described. A stop screw 144 adjustably mounted in plate 139 limits the upward swinging movement of shoe 141 under the influence of spring 143.

As shown in Fig. 14, the lower end portion of 15 die 105 is bifurcated so that the tines at the lower end of the die occupy positions at opposite sides of anvil 104a and shoe 141, said shoe being in width approximately the same as the width of 20 the slot between the tines at the lower end of the die.

The uppermost wire-feeding roll 101 is fixed in position upon the forward end of a horizontally disposed spindle 145 rotatably mounted eccentrically within a rocker sleeve 146 journaled within a bearing provided on the head frame 14. The axes of spindle 145 and rocker sleeve 146 are disposed in a horizontal plane at right angles with respect to a vertical plane passing through the axis of spindle 145 and the axis of lowermost 25 feed roll 102.

30 Rigidly clamped in position upon the rocker sleeve 146 by means of a screw 147 (Figs. 9 and 13) is an upwardly projecting lever arm 148 to which is connected one end of a spring 149 which 35 acts upon the lever arm 148 in a direction to yieldingly urge spindle 145 and the uppermost feed roll 101 toward the axis of the lower feed roll 102 so that the wire W is forcibly gripped by the two feed rolls. An adjustable stop screw 40 150, carried by the split hub of lever arm 148 engages the top of the base portion of head frame 14 to prevent contact between the two feed rolls when there is no wire between them.

45 The lowermost wire-feeding roll 102 is fixed in position upon the forward end of a horizontally disposed spindle 151 (Figs. 5, 10 and 12) which is disposed directly below, and parallel with, the spindle 145 of the uppermost feed roll.

The lower spindle 151 extends rearwardly beyond the upper spindle 145 and has mounted thereon the hub of a clutch lever 152 which may be constructed the same as the clutch lever shown in Fig. 6. This clutch lever 152 is vibrated by the double eccentric 54 (Fig. 7) acting through 55 a pitman 153 (Figs. 5 and 10) whose upper end is provided with a strap encircling said eccentric and whose lower end is pivotally and adjustably connected with the outer portion of the clutch lever 152. When this clutch lever is vibrated by the eccentric, it is effective upon its upward stroke only to turn the lower spindle 151 a predetermined distance, and this distance may be varied or regulated by adjustment of a screw 54 (Fig. 12) extending through and having threaded engagement with a block 155 that is mounted within a radial slot 156 formed in the arm of clutch lever 152.

60 As shown, particularly in Figs. 10 and 12, the lower spindle 151 carries a gear 157 which drives a gear 158 fast on the upper spindle 145. Thus the two spindles 145 and 151 are intermittently operated step-by-step in timed relation with the movements of the cross-head while shaft 33 is being operated.

65 The hub of the lowermost gear 157 (Figs. 9

and 12) is embraced by a pair of brake arms 159 which are pivotally anchored at 160 to the base portion of head frame 14. A screw 161 extends loosely through an aperture in the uppermost arm 159 and its lower end portion occupies a threaded aperture provided in the lowermost arm 159. A coiled spring 162 disposed between the uppermost brake arm and the head of screw 161 causes both brake arms to yieldingly grip the hub of the lowermost gear thereby to hold the wire-feeding rolls 101 and 102 against rotative displacement between movements thereof.

The uppermost feed roll 101 (Fig. 9) is made upon its periphery with a shallow circumferential groove 163 that is occupied by the portion of the wire that is between the two feed rolls. This groove serves to hold the wire against lateral displacement relatively to the feed rolls.

As shown by the magnified view of Fig. 18, the lowermost feed roll 102 is made upon its periphery with transversely disposed peaked ribs or salients 164 thereby producing burrs or projections 165 (Fig. 16) upon the bottom side of the wire W as it passes between the feed rolls. Thus, when a blank 166 is severed from the advance or leading end of the wire W, it is scored at intervals throughout its length and upon its bottom side as indicated by dotted lines in Fig. 17. When said blank is formed into a staple as shown in Fig. 16, the scored side of the wire is upon the interior of the staple and the projecting burrs thereof serve to anchor the staples securely within the material into which it is driven.

When the feed slide 133 (Fig. 15) is actuated by spring 137 to transfer a finished staple S from anvil 104a to the rail 140 of the staple-holding magazine, the said staple is slid forward by the feed slide into a position between the rail 140 and a spring-pressed shoe or detent 167 (Figs. 19, 21 and 23). This shoe yieldingly clamps the staple against said rail and holds it against backward movement with the feed slide when cam 128 on the cross-head acts through lever 129 (Fig. 15) to retract the feed slide during the downward stroke of the cross-head.

As shown in Figs. 21 and 23, the shoe 167 is an angular block of metal slidably mounted within a recess formed in the body 168 of the magazine and yieldingly urged toward rail 140 by a pair of coiled springs 169.

The body 168 of the magazine is of trough-like form and the rail 140 is a vertically disposed rib provided at the bottom of the trough 172. A cap plate 170 fastened in position upon the top of body 168 closes all of the top of the trough, except for a narrow slot 171 (Figs. 19 and 24 through which the contents of the magazine may be observed by the operator.

At its forward end the magazine body 168 is made with a head 173 (Figs. 15 and 20) whose lower end is coincident with a horizontal plane that is tangent to the bottom of feed roll 18 so that said lower end is immediately adjacent to, and practically in contact with, the upper 22 of the shoe.

Upon its front side the head 173 is formed with a vertical T-shaped channel 174 (Figs. 19 and 20) within which the driver 26 is mounted for endwise reciprocatory movement therein, said driver also being T-shaped in cross-section to fit said channel as shown in Fig. 21. When the driver 26 occupies its uppermost position the trough 172 of the magazine body communicates with the vertical channel 174 and one end of

rail 140 is immediately adjacent to, and in register with, the same.

When the shaft 33 is first started with the staple magazine empty the staple-making mechanism functions to produce staples and deliver the same into the magazine until the file of staples built up on rail 140 is of such length that thereafter each feeding stroke of slide 133 moves the entire file of staples endwise and forwardly on rail 140 until the foremost staple of said file is brought to bear against stop shoulders 175 (Fig. 19) within the vertical channel 174 while the driver 26 is elevated so that when the driver descends said foremost staple is driven downwardly through the channel 174 and into the shoe.

The tread of the last 20 (Fig. 15) is provided with a sheet metal plate 176 by which the extremities of the staple legs are upset or clinched.

Also, the legs of the staples may be produced slightly divergent, as shown in Fig. 16, so that when forced into channel 174 by the feed slide each will frictionally grip the opposite sides thereof.

The wiper element 27, hereinabove referred to, is pivotally supported immediately alongside of the magazine head 173 as shown in Figs. 5 and 9. A link 176 (Figs. 7, 10 and 11) connects this wiper element with a slide 177 mounted in ways provided upon the bottom side of head frame 14 adjacent to the vertical shaft 43 so that it is movable toward and from the latter. Slide 177 carries a roll or truck 178 which is yieldingly held by a spring 180 against a star cam 179 fast on shaft 43. As indicated by dotted lines in Fig. 7, this spring bears at its one end against a shoulder or frame 14 and at its opposite end against a lug 181 (Fig. 12) provided upon the top side of slide 177. As will be clear, cam 179 acts through slide 177 and link 176 to continually vibrate wiper 27 while shaft 43 is intermittently rotated step-by-step by shaft 33 and also while shaft 43 is continuously rotated by gear 91.

Wiper element 27 forces or irons the pulled-over portion of the skirt of the upper down onto the innersole progressively as it leaves the feed rolls 18 and 19 and is especially designed for use while the feed rolls are continuously driven and cemented shoe parts are being operated upon.

As herein shown, the prime power shaft 29 may be continuously driven by an electric motor 182 (Figs. 1 and 2) mounted within the column 10. As shown, the armature shaft of motor 182 is provided with a stepped pulley 183 connected by a belt 184 with a stepped pulley 185 fast on a countershaft 186. Countershaft 186 is journaled in a bearing provided on the box-like bracket 81 (Figs. 7 and 10) and one end thereof projects into the latter where it is connected by miter gears 187 with prime power shaft 29. The circuit of motor 182 is controlled, as usual, by a manually operated switch (not shown) mounted upon the exterior of column 10.

The slide carrier or slide 39 (Figs. 9 and 11) which carries the front feed roll and shafts 31 and 34, is slidably mounted within a recess provided upon one side of the upstanding wall 14b of the head frame and is retained within said recess by a plate 188 fastened by screws to the frame, said slide being movable in its ways in a direction lengthwise of shafts 34 and 35. Normally a spring 189 yieldingly urges slide 39 rearwardly so as to hold the feed roll 19 against or close to the feed roll 18 when a shoe upper is not

between said rolls. Spring 189 is mounted within a chamber 190 formed longitudinally in carrier slide 39 and one end of said spring is anchored at 191 to the slide while its opposite end is connected with a screw 192. This screw is provided with a nut 193 bearing against a washer 194 which in turn bears against the rear ends of the frame wall 14b and plate 188. Screw 192 extends loosely through the washer 194 so that by rotatively adjusting nut 193 screw 192 may be shifted endwise to regulate the tension of spring 189.

Journaled in bearings provided at the rear ends of wall 14b and plate 188 is a rock-shaft 195 having fixed thereon a radial arm 196 normally bearing against the rear end of slide 39. Shaft 195 also has fixed on it an arm 197 to which is pivotally connected one end of a link 198.

As shown in Figs. 1 and 2, the link 198 extends downwardly from arm 197, through column 10 and into pedestal 11 where its lower end is pivotally connected to an arm 199 fast on a rock-shaft 200 journaled at its opposite ends in bearings on pedestal 11. This rock-shaft carries a pinion 201 meshing with a gear 202 fast on a second rock-shaft 203 also journaled at its opposite ends in bearings provided on pedestal 11. Treadle 24 is fast on rock-shaft 203 and gear 202 is made larger than pinion 201 so that a relatively small downward movement of treadle 24 will act through gear 202 and pinion 201 to effect a greater downward movement of link 198. It will be clear that when treadle 24 is pressed downwardly it acts through the connections described to swing arm 196 toward the right in Fig. 11 and said arm will shift slide 39 forwardly thereby separating the feed rolls 18 and 19 to permit the shoe upper to be inserted, or withdrawn from, between said feed rolls.

It will be clear that the purpose of the slot 47 and key 48 (Fig. 11) is to permit of endwise movement of shaft 34 relatively to the tubular hub of gear 45 when slide 39 is thus adjusted on the frame, so as to maintain driving connection between said shaft and hub at all times.

The lower end of the pitman 53 (Figs. 5 and 6) is pivotally connected to a block 204 slidably mounted within a radial slot 205 formed in the arm of clutch lever 51, said block being made with a threaded hole extending therethrough which is occupied by a screw 206 carried by arm 51. This screw normally holds block 204 in fixed position within slot 205 but by rotation thereof said block may be adjusted radially to vary the effective length of arm 51. It will thus be clear that by varying the effective length of arm 51 the length of the step movements imparted to the work, and therefore the distance between the driven staples, may be varied as desired within limits determined by the lengths of slot 205 and of screw 206.

In the preferred embodiment of this invention, and as shown in Fig. 26, the conicity of feed rolls 18 and 19, and the relative disposition of their axes, is such that the lower ends of said rolls are closer together than the upper ends thereof. That is to say, the opposed upper-engaging surfaces at the bite of said rolls diverge slightly from their lower larger ends toward their smaller upper ends so that the upper-gripping action of the rolls is greatest at their larger ends and therefore it is possible for slippage to occur between the top portion of the upper flange or skirt and the rolls as the latter traverse said skirt or flange.

From the above description it will be ob-

served that a distinguishing feature of the illustrated embodiment of my invention consists in so constructing and arranging the two feed rolls that the portion of the skirt of the upper which is gripped between said rolls, is maintained by the latter in an oblique outwardly inclined position so that it is disposed at an obtuse angle with respect to the direction of the upper-engaging stroke of the wiper element 27 so that the latter 10 delivers a glancing blow against the upper alongside of said gripped portion thus avoiding injury to the same. This is a distinct advantage derived from a pair of feed rolls constructed and operating substantially as described. Another advantage 15 is that the pull of the rolls upon the gripped portion of the skirt of the upper as said rolls traverse the latter, is also effected in an outward oblique direction which tends to pull the upper snugly and forcibly around the corner of the last in a direction toward the middle of the latter.

What I claim is:

1. A machine for lasting a shoe upper while said upper and an innersole are assembled upon a last, said machine including, in combination, a 25 upper lasting mechanism comprising a pair of rotatable upper-gripping members for engaging the skirt of the upper, and means for rotating said members intermittently to cause the same to traverse the skirt of the upper step-by-step while 30 said last and shoe parts are supported and guided past said members so as to cause the latter to progressively pull the same inwardly toward the middle of the innersole.

2. A machine for lasting a shoe upper while 35 said upper and an innersole are assembled upon a last, said machine including, in combination, a pair of feed rolls for gripping the skirt of the upper, and means for rotating said feed rolls intermittently to cause the same to traverse the 40 skirt of the upper step-by-step while said last and shoe parts are supported and guided past said rolls so as to cause the latter to progressively pull the same inwardly toward the middle of the innersole.

45 3. A lasting machine constructed in accordance with claim 2 and wherein the axes of said feed rolls are disposed at an angle relatively to each other.

4. A machine for lasting a shoe upper while 50 said upper and an innersole are assembled upon a last, said machine including, in combination, a pair of feed rolls for gripping the skirt of the upper; means for rotating said feed rolls intermittently to cause the same to traverse the skirt of the 55 upper step-by-step while said last and shoe parts are supported and guided past said rolls so as to cause the latter to progressively pull the same inwardly toward the middle of the innersole, and means for guiding said last and shoe parts in their movement past said feed rolls.

5. A lasting machine constructed in accordance with claim 4 and wherein the axes of said feed rolls are disposed at an angle relatively to each other.

6. A machine for lasting a shoe upper while 65 said upper and an innersole are assembled upon a last, said machine including, in combination, a pair of feed rolls for gripping the marginal portion of the skirt of the upper to pull the same inwardly toward the middle of the innersole; means for rotating said feed rolls intermittently to cause the same to traverse the skirt of the 70 upper step-by-step while said last and shoe parts are supported and guided past said rolls so as to cause the latter to progressively pull the same

inwardly on to the innersole; a work-rest by which said last and shoe parts are guided in their movement past said feed rolls, and means for driving fasteners one at a time into said upper and innersole during periods of rest of said rolls.

7. A lasting machine constructed in accordance with claim 6 and wherein the axes of said feed rolls are disposed at an angle relatively to each other.

8. A machine for lasting a shoe upper while said upper and an innersole are assembled upon a last, said machine including, in combination, a pair of feed rolls for gripping the skirt of the upper; means for rotating said rolls intermittently to cause the same to traverse the skirt of the upper step-by-step while said last and shoe parts are supported and guided past said rolls so as to cause the latter to progressively pull the same inwardly toward the middle of the innersole; a fixed frame by which said feed rolls are supported, and a work-rest on said frame co-acting with one of said rolls to guide said last and shoe parts in their movement past said feed rolls.

9. A lasting machine constructed in accordance with claim 8 and wherein the axes of said feed rolls are disposed at an angle relatively to each other.

10. A machine of the class described for lasting a shoe upper while said upper and an innersole are assembled upon a last, said machine including, in combination, a pair of conical feed rolls for gripping the skirt of the upper, and means for rotating said rolls to cause the same to traverse the skirt of the upper while said last and shoe parts are supported and guided past said rolls so as to cause the latter to progressively pull the same obliquely inwardly toward the middle of the innersole.

11. A machine of the class described constructed in accordance with claim 10 and wherein in the opposed portions of the peripheries of said rolls at the bite between the latter diverge toward the smaller ends of said rolls so that the latter grip the upper with greater force at their larger ends than at their smaller ends.

12. A machine of the class described for lasting a shoe upper while said upper and an innersole are assembled upon a last, said machine including, in combination, a pair of conical feed rolls for gripping the skirt of the upper, one of said feed rolls being made at its larger end with a convex innersole-engaging abutment surface, and means for rotating said rolls to cause the same to traverse the skirt of the upper and progressively pull the same obliquely toward the middle of the innersole.

13. A machine of the class described for lasting a shoe upper while said upper and an innersole are assembled upon a last, said machine including, in combination, a pair of conical feed rolls for gripping the skirt of the upper; two shafts each of which supports one of said rolls, the axes of said shafts being relatively disposed at an acute angle, and means for rotating said shafts and rolls to cause the latter to traverse the skirt of the upper and progressively pull the same obliquely toward the middle of the innersole.

14. A machine of the class described for lasting a shoe upper while said upper and an innersole are assembled upon a last, said machine including, in combination, a pair of feed rolls for gripping the marginal portion of the skirt of the upper; means for rotating said feed rolls to cause the same to traverse the skirt of the upper while said last and shoe parts are supported and guided

past said rolls so as to cause the latter to progressively pull the same obliquely inwardly toward the middle of the innersole; a frame providing a stationary support for one of said rolls; a carrier 5 movably mounted on said frame and by which the other roll is supported so that it is movable toward and from said first-mentioned roll when said carrier is adjusted on said frame; means operable to yieldingly urge said carrier in a direction 10 to cause said rolls to grip the skirt of the upper; a wiper element, and means for operating said wiper element to cause the same to press the impulled portion of the skirt down on to the innersole.

15. A machine of the class described for lasting a shoe upper while said upper and an innersole are assembled upon a last, said machine including, in combination, a pair of feed rolls for gripping the marginal portion of the skirt of the upper, said rolls having their axes disposed at an angle relatively to each other; means for rotating said feed rolls to cause the same to traverse the skirt of the upper while said last and shoe parts are supported and guided past said rolls so 20 as to cause the latter to progressively pull the same obliquely inwardly toward the middle of the innersole; a frame providing a stationary support for one of said rolls; a carrier movably mounted on said frame and by which the other roll is supported so that it is movable toward and from said first-mentioned roll when said carrier is adjusted on said frame, and means operable to yieldingly urge said carrier in a direction to cause said rolls to grip the skirt of the upper.

16. A machine of the class described for lasting a shoe upper while said upper and an innersole are assembled upon a last, said machine including, in combination, a pair of feed rolls for gripping the skirt of the upper; means for rotating said feed rolls to cause the same to traverse the skirt of the upper circumambiently while said last and shoe parts are supported and guided past said rolls so as to cause the latter to progressively pull the same obliquely inwardly toward the middle of the innersole; a frame providing 30 a stationary support for one of said rolls; a carrier movably mounted on said frame and by which the other roll is supported so that it is movable toward and from said first-mentioned roll when said carrier is adjusted on said frame, and means operable to yieldingly urge said carrier in a direction to cause said rolls to grip the skirt of the upper.

17. A machine of the class described for lasting

a shoe upper while said upper and an innersole are assembled upon a last, said machine including, in combination, a pair of feed rolls for gripping the marginal portion of the skirt of the upper; means for rotating said feed rolls to cause the same to traverse the skirt of the upper circumambiently while said last and shoe parts are supported and guided past said rolls so as to cause the latter to progressively pull said marginal portion obliquely toward the middle of said innersole thereby to lay an adjacent portion of said skirt on to the outer face of the innersole, and means for guiding said last and shoe parts in their movement past said feed rolls.

18. A machine of the class described for lasting a shoe upper while said upper and an innersole are assembled upon a last, said machine includ-

ing, in combination, a pair of feed rolls for gripping the marginal portion of the skirt of the upper; means for rotating said feed rolls intermittently to cause the same to traverse the skirt of the upper circumambiently step-by-step while said last and shoe parts are supported and guided past said rolls so as to cause the latter to progressively pull said marginal portion obliquely inwardly relatively to said innersole toward the middle of the latter thereby to lay an adjacent portion of said skirt on to the outer face of the innersole; means for guiding said last and shoe parts in their movement past said feed rolls, and means for automatically driving a fastener into said skirt and innersole adjacent to said feed rolls during each period of rest of the latter.

19. A machine for lasting a shoe upper while said upper and an innersole are assembled upon a last, said machine including, in combination, a pair of feed rolls for gripping the marginal portion of the skirt of the upper; means for rotating said feed rolls intermittently to cause the same to traverse the skirt of the upper circumambiently step-by-step while said last and shoe parts are supported and guided past said rolls so as to cause the latter to progressively pull said marginal portion obliquely inwardly relatively to said innersole toward the middle of the latter thereby to lay an adjacent portion of said skirt on to the outer face of the innersole; means for guiding said last and shoe parts in their movement past said feed rolls, and means for automatically driving a staple into said skirt and innersole adjacent to said feed rolls during each period of rest of the latter.

20. A machine for lasting a shoe upper while said upper and an innersole are assembled upon a last, said machine including, in combination, a pair of feed rolls for gripping the marginal portion of the skirt of the upper; means for rotating said feed rolls intermittently to cause the same to traverse the skirt of the upper circumambiently step-by-step while said last and shoe parts are supported and guided past said rolls so as to cause the latter to progressively pull said marginal portion obliquely inwardly relatively to said innersole toward the middle of the latter thereby to lay an adjacent portion of said skirt on to the outer face of the innersole; means for guiding said last and shoe parts in their movement past said feed rolls, and means for automatically fabricating a staple during each period of rest of said roll and simultaneously driving a previously fabricated staple into said upper and innersole.

21. In a lasting machine of the class described, the combination with a pair of intermittently rotated upper-gripping feed rolls, of a frame by which said rolls are supported; a cross-head mounted on said frame for reciprocatory movement; a fastener-driving element carried by said cross-head; a channel on said frame within which said driving element is mounted for reciprocatory movement with said cross-head; a shaft that is continuously rotated in timed relation with respect to the intermittent movements of said feed rolls; a rotatably supported crank-arm provided with a wrist pin; a connecting rod connecting said wrist pin with said cross-head; a spring yieldingly holding said cross-head normally at the limit of its movement in one direction with said driving element at the limit of its driving stroke; means carried by and rotating with said shaft operable during each revolution of the latter to swing said crank arm from a dead center position at one side of its axis of rotation

10 to a position just beyond dead center position at the opposite side of said axis to stress said spring and then release said arm thereby to permit said spring to effect a fastener-driving stroke of said cross-head independently of said shaft, and means for feeding fasteners one at a time into said channel in timed relation with respect to the reciprocatory movements of said driving element so that each fastener is driven into the work by said driving element when the cross-head is actuated by said spring and while said feed rolls are at rest.

22. In a lasting machine of the class described the combination with a pair of intermittently rotated upper-gripping feed rolls, of a frame by which said rolls are supported; a cross-head mounted on said frame for reciprocatory movement; means for reciprocating said cross-head in timed relation with the movements of said feed rolls; a fastener driving element carried by said cross-head; a channel on said frame within which said driving element is mounted for reciprocatory movement with said cross-head; an anvil fixedly supported on said frame; a wire-cutting blade fixed in position on said frame adjacent to said anvil; a die mounted on said cross-head and cooperating with said blade and anvil; a movably supported shoe occupying a position between said die and said anvil; means for intermittently feeding wire into position between said shoe and said anvil so that when said cross-head is moved in one direction a staple blank is severed from said wire and formed into a staple on said anvil, said die acting through said shoe to 25 straighten the top portion of the staple, and means for automatically feeding said staple toward said channel during the retracting movement of said driving element.

23. In a lasting machine of the class described 40 the combination of claim 22 wherein a magazine is provided on said frame between said anvil and said channel and into which the staples formed on said anvil are delivered one at a time by said staple-feeding means so as to maintain within 45 said magazine a file of staples which is moved endwise by each staple as the latter is transferred from the anvil to one end of the magazine by said feeding means thereby to deliver into said channel a staple from the opposite end of said magazine.

24. The combination of claim 22 including also 50 a magazine on said frame between said anvil and said channel into one end of which the staples formed on said anvil are delivered one at a time by said staple-feeding means so as to maintain within said magazine a file of staples which is moved endwise by each staple as the latter is transferred from the anvil to one end of the magazine by said feeding means thereby to move into said channel the endmost staple at the opposite end of said magazine, and a spring-pressed detent adjacent to the entrance end of the magazine for engaging each staple fed into the latter to hold it against movement toward 55 said anvil.

25. In a lasting machine of the class described, the combination of claim 22 and wherein said staple feeding means includes a reciprocatory staple-feeding member movably mounted on said frame; a lever pivotally mounted on said frame for moving said member in one direction; a spring for moving said member in the opposite direction, and a cam on said cross-head for operating said lever.

70 26. In a lasting machine of the class described,

the combination with a pair of feed rolls for gripping the skirt of a shoe upper and operable when rotated to traverse said skirt circumambiently, of a continuously rotated prime power shaft; power-transmitting mechanism through which said prime power shaft continuously rotates said rolls when said mechanism is connected with said shaft; power-transmitting mechanism through which said prime power shaft intermittently rotates said rolls when said mechanism is connected with said shaft, and manually controlled mechanism that is adjustable to connect either power-transmitting mechanism with said prime power shaft to the exclusion of the other power-transmitting mechanism.

27. In a lasting machine of the class described, the combination with a pair of feed rolls for gripping the skirt of a shoe upper and operable when rotated to traverse said skirt circumambiently, of a continuously rotated prime power shaft; power-transmitting mechanism through which said prime power shaft continuously rotates said rolls when said mechanism is connected with said shaft; power-transmitting mechanism through which said prime power shaft intermittently rotates said rolls when said mechanism is connected with said shaft, and manually controlled mechanism that is adjustable to connect either power-transmitting mechanism with said prime power shaft to the exclusion of the other power-transmitting mechanism, or to maintain both of said mechanisms disconnected from said prime power shaft.

28. In a lasting machine of the class described, the combination of claim 27 wherein said last-mentioned manually controlled mechanism includes a control member supported for movement back and forth within predetermined limits, and a spring for yieldingly holding said member at the limit of its movement in one direction with both of said power-transmitting mechanisms disconnected from said prime power shaft, said member being manually adjustable to occupy a position at the limit of its movement in the opposite direction thereby to connect one of said power-transmitting mechanisms with said prime power shaft and also manually adjustable to occupy an intermediate position thereby to connect the other power-transmitting mechanism with said prime power shaft.

29. In a machine for lasting a shoe upper while said upper and an innersole are assembled on a last, the combination with lasting mechanism comprising a pair of upper-gripping members which are rotated to pull the skirt of the upper inwardly relatively to the innersole toward the middle of the latter and simultaneously to feed said skirt circumambiently step-by-step past said lasting mechanism, of automatic fastener-driving devices operable to drive individual fasteners into said upper and innersole during periods of rest of said shoe parts, and means through which the operator of the machine may at will adjust said mechanism to vary the length of the step movements imparted to said shoe parts thereby to vary the distance between adjacent fasteners that are driven into the work.

30. In a lasting machine of the class described, the combination of claim 29 and wherein the automatic fastener-driving devices are constructed and arranged to insert a metal staple."

31. A machine for lasting a shoe upper while said upper and an innersole are assembled upon a last, said machine including, in combination, a pair of rolls for gripping the skirt of the upper,

and means for rotating said rolls to cause the same to progressively traverse the skirt of the upper while said last and shoe parts are supported and guided past said rolls so as to cause the latter to simultaneously stress the gripped portion of the skirt obliquely inwardly relatively to the innersole.

32. A lasting machine constructed in accordance with claim 31 and wherein the axes of said rolls are disposed at an angle relatively to each other.

15 33. A machine for lasting a shoe upper while said upper and an innersole are assembled upon a last, said machine including, in combination, a pair of rolls for gripping the skirt of the upper; means for rotating said rolls to cause the same to progressively traverse the skirt of the upper while said last and shoe parts are supported and guided past said rolls so as to cause the latter to simultaneously stress the gripped portion of the skirt obliquely inwardly relatively to the innersole; a wiper element, and means for operating said wiper element to cause the same to press the impulled portion of the skirt down on to the innersole.

20 34. A machine for lasting a shoe upper while said upper and an innersole are assembled upon a last, said machine including, in combination, a pair of rolls for gripping the skirt of the upper; means for intermittently rotating said rolls to cause the same to progressively traverse the skirt of the upper while said last and shoe parts are supported and guided past said rolls so as to cause the latter to continually stress the gripped portion of the skirt obliquely inwardly relatively to the innersole, and mechanism for periodically driving a fastener into said skirt and innersole while said parts are at rest.

25 35. A machine for lasting a shoe upper while said upper and an innersole are assembled upon a last, said machine including, in combination, a pair of rolls for gripping the skirt of the upper; means for rotating said rolls intermittently to cause the same to progressively traverse the skirt of the upper while said last and shoe parts are supported and guided past said rolls so as to cause the latter to continually stress the gripped portion of the skirt obliquely inwardly relatively to the innersole; mechanism for periodically driving a fastener into said skirt and innersole while said parts are at rest, and means to provide for varying the spacing between the driven fasteners.

30 36. A machine for lasting a shoe upper while said upper and an innersole are assembled upon a last, said machine including, in combination, a pair of conical rolls for gripping the skirt of the upper disposed so that when rotated said skirt is fed between said rolls circumambiently while the rolls exert a component force upon the gripped portion of said skirt in a direction to urge the same obliquely inwardly relatively to said innersole; means for rotating said rolls; a wiper element, and means for operating said wiper element to cause the same to wipe the in-pulled portion of the skirt down on to the innersole.

35 37. A machine for lasting a shoe upper while said upper and an innersole are assembled upon a last, said machine including, in combination, a pair of conical rolls for gripping the skirt of the upper, means for intermittently rotating said rolls to cause the same to progressively traverse the skirt of the upper step-by-step while continually urging the gripped portion of the same inwardly relatively to the innersole; a wiper ele-

ment; means for operating said wiper element to cause the same to press the in-pulled portion of the skirt down on to the innersole, and means for attaching the in-pulled portion of the skirt to the innersole.

38. A machine for lasting a shoe upper while said upper and an innersole are assembled upon a last, said means including, in combination, a pair of conical rolls for gripping the skirt of the upper; means for intermittently rotating said rolls to cause the same to progressively traverse the skirt of the upper step-by-step while continually urging the gripped portion of the same inwardly relatively to the innersole; a wiper element; means for operating said wiper element to cause the same to wipe the in-pulled portion of the skirt down on to the innersole; mechanism for periodically driving a fastener into said skirt and innersole, and means to provide for varying the spacing between the driven fasteners.

39. The method of lasting a shoe upper while said upper and an innersole are assembled on a last which consists in first placing the skirt of the upper in position between a pair of rolls and thereafter manually supporting and guiding said last and shoe parts, while said rolls are in gripping engagement with said skirt and are rotated, so as to cause said rolls to feed said skirt between the same while at the same time exerting a component force upon said skirt in a direction to urge the gripped portion of said skirt obliquely inwardly relatively to the innersole, and means to provide for varying the spacing between the driven fasteners.

40. The method of lasting a shoe upper while said upper and an innersole are assembled on a last which consists in first placing the skirt of the upper in position between a pair of rolls whose axes are disposed at an angle relatively to each other and thereafter manually supporting and guiding said last and shoe parts while said rolls are in gripping engagement with said skirt and are rotated, so as to cause said rolls to feed said skirt between the same while at the same time exerting a component force upon said skirt in a direction to urge the gripped portion of said skirt obliquely inwardly relatively to the innersole, and means to provide for varying the spacing between the driven fasteners.

41. The method of lasting a shoe upper while said upper and an innersole are assembled on a last which consists in first placing the skirt of the upper in position between a pair of rolls and thereafter manually supporting and guiding said last and shoe parts, while said rolls are in gripping engagement with said skirt and are intermittently rotated, so as to cause said rolls to intermittently feed said skirt between the same while at the same time exerting a component force upon the gripped portion of said skirt in a direction to urge the same inwardly relatively to the innersole as said rolls traverse said skirt, and in periodically driving a fastener into said skirt and innersole while the latter are momentarily at rest.

42. A machine for lasting a shoe upper while said upper and an innersole are assembled upon a last, said machine including, in combination, a pair of rolls for gripping the skirt of the upper; means for rotating said rolls to cause the same to progressively traverse the skirt of the upper while said last and shoe parts are supported and guided past said rolls so as to cause the latter to simultaneously urge the gripped portion of the same obliquely inwardly relatively to the innersole; a wiper element, and means for operating

said wiper element to cause the same to wipe the in-pulled portion of the skirt down on to the innersole.

43. A machine for lasting a shoe upper while said upper and an innersole are assembled upon a last, said machine including, in combination, a pair of rolls for gripping the skirt of the upper; means for intermittently rotating said rolls to cause the same to progressively traverse the skirt of the upper while said last and shoe parts are supported and guided past said rolls so as to cause the latter to simultaneously urge the gripped portion of the same inwardly relatively to the innersole, and mechanism for periodically driving a fastener into said skirt and innersole while said parts are at rest.

44. A machine for lasting a shoe upper while said upper and an innersole are assembled upon a last, said machine including, in combination, a pair of rolls for gripping the skirt of the upper constructed and arranged to progressively traverse said skirt while said last and shoe parts are supported and guided past said rolls so as to cause the latter to simultaneously urge the gripped portion of the skirt obliquely inwardly relatively to the innersole, and means for rotating said rolls.

45. In a machine for lasting a shoe upper while said upper and an innersole are assembled upon a last, the combination of claim 44 wherein there is also provided means operable to cause said rolls to yieldingly grip said skirt.

46. A lasting machine comprising a pair of oppositely rotated work-gripping, work-stressing and work-feeding rolls; a reciprocatory wire-cutting, fastener-forming and fastener-driving crosshead; a fixed anvil with which said crosshead co-operates to form staples; a fixed wire cutter with which said crosshead co-operates; a spring yieldingly urging said crosshead toward the limit of its movement in one direction; means for intermittently retracting said crosshead against the pressure of said spring to the limit of its movement in the opposite direction and thereupon releasing the crosshead to permit said spring to effect a driving, cutting and forming stroke thereof; means for intermittently feeding one end of a supply wire of indeterminate length into position to be operated upon by said crosshead in timed relation with the movements of the latter so that when said crosshead is actuated by said spring a measured length of wire is severed from said supply wire and formed into a staple on said anvil, and staple feeding mechanism operable during the retracting movement of the crosshead to move each formed staple toward staple-driving position relatively to said crosshead.

47. A lasting machine constructed in accordance with claim 46 and wherein said wire feeding means is also operable to produce holding burrs upon said supply wire as the latter is fed forward.

48. A lasting machine constructed in accordance with claim 46 and wherein said wire feeding means comprises a pair of intermittently operated wire feeding rolls; a shaft for one of said rolls; a bushing within which said shaft is eccentrically journaled; a spring urging said bushing rotatively in one direction to cause said rolls to grip said supply wire, and a handle on said bushing by means of which it is manually rotated to separate said rolls.

CARL F. HAMMANN.
